UNITED STATES PATENT OFFICE.

WILLIAM R. FOX, OF GRAND RAPIDS, MICHIGAN.

STOP DEVICE FOR TYPE-WRITERS.

No. 839,746.

Specification of Letters Patent.

Patented Dec. 25, 1906.

Application filed July 17, 1905. Serial No. 270,066.

To all whom it may concern:

Be it known that I, WILLIAM R. Fox, a citizen of the United States, residing at the city of Grand Rapids, county of Kent, State of Michigan, have invented certain new and useful Improvements in Stop Devices for Type-Writers, of which the following is a specification.

This invention relates to improvements in stops for the carriages of type-writing machines, and is more particularly adapted for use as a stop in connection with tabulating devices for type-writing machines.

The object of this invention is to provide an improved detachable adjustable stop which is simple and easy to construct, which is compact, occupying very little space along the stop-bar, and which can be very readily attached and detached and is very secure when in position.

Further objects relating to structural details will more definitely appear from the detailed description to follow.

I accomplish the objects of my invention by the devices and means described in the following specification.

The invention is clearly defined, and pointed out in the claims.

A structure embodying the features of my invention is clearly illustrated in the accompanying drawings, forming a part of this specification, in which—

Figure 1 is an enlarged rear elevation view of one of my improved stops in place on the stop-bar of a tabulating device of a type-writer. Fig. 2 is an enlarged sectional side view taken on line 2 2 of Figs. 1 and 4. Fig. 3 is an enlarged sectional end view taken on line 3 3 of Fig. 2. Fig. 4 is an enlarged bottom view of my improved stop in connection with a portion of the stop-bar. Fig. 5 is an enlarged top view of my improved stop with a portion removed.

In the drawings, all of the sectional views are taken looking in the direction of the little arrows at the ends of the section-lines, and similar letters of reference refer to similar parts throughout the several views.

Referring to the drawings, A represents a part of the stop-bar of a tabulator for a type-writing machine, provided with a series of teeth A', forming a series of intermediate notches A''. On this stop-bar A is mounted one of my improved stops, as shown in sectional detail in Figs. 2 and 3.

The body B of my improved stop is

stamped or otherwise shaped from sheet metal of the same thickness as the width of one of the notches A''. The sides of the body B of said stop are slotted transversely, 60 as shown in Fig. 4, the width of said slot corresponding to the thickness of the solid portion of said stop-bar A—that is, it corresponds to the body part of the bar not including the teeth. The said sides of the 65 body B of said stop are parallel to each other, so that the said body may be readily and easily applied, the parts b b being received in the notches A'' of the stop-bar A, thus firmly, efficiently, and detachably holding the said 70 stop in position, so that the type-writer carriage can be arrested at any desired point. A portion of the body B is bent upward, so as to form the finger-piece B'. One of the parts b is cut away, so that only a single thickness of 75 metal is presented as a contact with the carriage.

The lever C, which is also preferably stamped out from sheet metal, consists of the finger-piece C', neck c, and catch C''. The 80 lever C is passed down sidewise through a slot c' in the top of the body B and is then turned so that the lever C will be held in place by the shoulders on each side of the neck c. When the stop is slipped over the stop-bar A, 85 the catch C'' will engage the lower side of the said stop-bar and is held normally in place by the spring D, which is suitably secured to the top of the body B by a screw D'. Any suitable means, however, may be used for securing said spring D to the frame B.

I have illustrated and described my improved adjustable and detachable stop in the form preferred by me on account of its simple and economical construction. I am aware 95 that the structural details may be considerably varied without, however, departing from my invention.

Having thus described my invention, what I claim as new, and desire to secure by Letters Patent, is—

1. In a stop device, the combination of a notched stop-bar; a U-shaped body having an upwardly-projecting finger, formed from sheet metal, the sides of which are slotted so 105 that the body may embrace the notched stop-bar and the edges of the slots engage the notches of said stop-bar; a lever, provided with a catch, passing down through a slot in said body, the said catch engaging the lower 110 edge of said stop-bar; and a spring secured to the top of said body, for holding said lever

normally in position, for the purpose specified.

2. In a stop device, the combination of a notched stop-bar; a body, having an upwardly-projecting finger, the sides of which are slotted so that the body may embrace the notched stop-bar and the edges of the slots engage the notches of said stop-bar; a lever provided with a catch, the said catch engaging the lower edge of said stop-bar; and a spring for holding said lever normally in position, for the purpose specified.

3. In a stop device, the combination of a notched stop-bar; a body having slotted sides, arranged to embrace the notched stop-bar; and a spring-pressed lever, provided with a catch, passing down through a slot in said body, the said catch engaging the lower edge of said stop-bar, for the purpose specified.

4. In a stop device, the combination of a notched stop-bar; a U-shaped body, formed from sheet metal, the sides of which are transversely slotted so that the body may embrace the said stop-bar and the edges of the slots engage the notches of the said stop-bar, and having an upwardly-projecting finger-piece integral therewith to serve as a handle; and a spring-lever provided with a catch as supported by said body, the said catch arranged to engage the lower edge of said stop-bar, for the purpose specified.

35

5. In a stop device, the combination of a notched stop-bar; a U-shaped body, formed from sheet metal, the sides of which are transversely slotted so that the body may embrace the said stop-bar and the edges of the slots engage the notches of the said stop-bar, and having an inwardly-projecting finger-piece integral therewith to serve as a handle; a lever provided with a catch as supported by said body, the said catch arranged to engage the lower edge of said stop-bar, and a spring secured to the top of said body for holding the said lever normally in position against the rack, for the purpose specified.

40

6. In a stop device, the combination of a notched stop-bar; a U-shaped body, formed from sheet metal, the sides of which are transversely slotted so that the body may embrace the said stop-bar and the edges of the slots engage the notches of the said stop-bar, and having an inwardly-projecting finger-piece integral therewith to serve as a handle; a lever provided with a catch as supported by said body, the said catch arranged to engage the lower edge of said stop-bar; and a spring secured to the top of said body for holding the said lever normally in position against the rack, for the purpose specified.

45

7. In a stop device, the combination of a notched stop-bar; a U-shaped body, formed from sheet metal, the sides of which are transversely slotted so that the body may embrace the said stop-bar and the edges of the slots engage the notches of the said stop-bar, and having an upwardly-projecting finger-piece integral therewith to serve as a handle; and a spring-lever provided with a catch as supported by said body, the said catch arranged to engage the lower edge of said stop-bar, for the purpose specified.

50

8. In witness whereof I have hereunto set my hand and seal in the presence of two witnesses.

WILLIAM R. FOX. [L. S.]
